UNITED STATES PATENT OFFICE.

HENRY M. SHEER, OF QUINCY, ILLINOIS, ASSIGNOR TO H. M. SHEER COMPANY, OF QUINCY, ILLINOIS, A CORPORATION OF ILLINOIS.

AIR-BLAST BURNER.

Application filed January 6, 1923. Serial No. 611,048.

My invention relates to an improvement in air blast burners.

In this particular invention, I have succeeded in producing perfect combustion with a wide range of flame adjustment, the flame being white instead of red and smoky as is the case with other burners of this type. Furthermore, I get a uniform and unvarying pressure of oil against the valve.

10 The principal features included in this new burner are an improved burner bowl, in connection with a multiple jet gas generator in the center thereof, together with the central air nozzle.

15 In the accompanying drawings:—

Fig. 1 is a view in elevation, and partly in section;

Fig. 2 is a perspective view of the air nozzle;

20 Fig. 3 is an enlarged section through the gas generator;

Fig. 4 is a plan view of the valve dial and pointer.

25 A, represents an air nozzle which includes a spider 1, cast from metal, and a down-draft air pipe 2, the lower end of which is held frictionally in the central body portion of the spider.

The numeral 3 represents the burner bowl 30 upon the upper edge of which the spider 1 rests.

The burner bowl is in the form of a cylinder, with an upturned edge 4, and having a bottom 5 which slopes toward the center 35 and up to the generator.

Ordinarily, the bottom of the burner bowl of this type slopes away from the center, and the object seems to be to vaporize the oil as it flows down the slope, and then burn 40 it about midway between the center and the edge of the bowl; but in this way the generator does not convert the oil into gas before it is delivered to the bowl. After the oil in my burner becomes generated, no raw oil, 45 or even oil vapor, is to be seen. The oil is converted into a dry gas which passes through the small holes 6 of the generator 7, and the incoming air through the nozzle A from the pipe 2 (as indicated by the arrow in Fig. 1) discharges so as to drive this 50 gas directly down to the bottom of the burner bowl. At this point ignition takes place, and, by the time this gas reaches the outer edge of the bowl, it is all consumed, 55 and the combustion is perfect.

The down-draft pipe 2 is preferably made of heavy sheet steel, and this pipe must be enough larger in diameter than the opening 8 in the bottom of the air nozzle A to prevent friction or resistance to the air 60 passing down through the pipe or tube 2.

While this pipe or tube is illustrated as passing straight down through the top of the stove into the burner, its construction and position can be modified to meet the 65 requirements of stoves or furnaces where an opening through the top cannot be arranged. For instance, this tube can be provided with an elbow, so it will pass through the front door of a furnace or stove. The 70 door opening would have to be closed, of course, so that all air must pass down through the pipe or tube 2.

Referring to the generator, the lower end of the draft nozzle must be placed the proper distance from the bottom of the burner below, and the generator must enter the lower end of the draft nozzle, so the small jets are about one-fourth inch above the bottom of the nozzle. 80

The generator is vertically adjustable for this purpose through the screw-threads 9 and 10. When thus adjusted, the incoming air carries the gas down with it, and forces a perfect mixture when the gas and air 85 strike the bottom of the bowl directly underneath.

The oil is supplied from a tank T through a suitable pipe controlled by a needle-valve 11, on which is fastened a dial 12 and pointer 13, so that the proper position of the valve can always be determined.

The action of this burner is the same when placed in a coal-burning stove as when placed in an oil-stove. A uniform and unvarying pressure of oil against the valve is necessary, and this may be provided in various ways, as for instance by means of a float (not shown) in the tank as fully set forth in patents already granted to me and 100 applications still pending.

I claim:

1. An air blast burner including a burner bowl having a substantially concave bottom with the center portion thereof sloping upward toward the center, a generator mounted upon said center portion at the top of the upwardly sloping sides, the sides of said generator being in alignment with and terminating in the sides of said gener- 110

ator, and an air pipe extending downward over the generator and having the discharge end thereof terminating below and in close proximity to the discharge point of said generator, the sides of said air pipe sloping toward the discharge point of said generator.

2. An air blast burner including a burner bowl, a generator mounted substantially at the center thereof, and having a discharge point adjacent the top, said burner bowl having a substantially concave bottom with the central portion thereof sloping upward toward the discharge point of said generator,

ator, an air supply pipe extending downward toward said generator, and an air nozzle supported upon said burner bowl and receiving the lower end of said air pipe, said nozzle having the lower discharge end thereof terminating below and in close proximity to the discharge point of said generator, and being tapered toward the generator for discharging the air toward the discharge point thereof at the center of the burner bowl.

In testimony whereof I affix my signature.

HENRY M. SHEER.
